H. R. SANDERS

COMBINED SIGNAL AND TROUBLE LAMP FOR AUTOMOBILES

Filed June 2, 1922

Henry R. Sanders,
Edward E. Blamey

Attorney

UNITED STATES PATENT OFFICE.

HENRY R. SANDERS, OF NORTH BEACH, MARYLAND.

COMBINED SIGNAL AND TROUBLE LAMP FOR AUTOMOBILES.

Application filed June 2, 1922. Serial No. 565,311.

My invention relates to automobile lighting systems and has special reference to that class of devices by which a driver may signal his movements to those behind him. The 5 object of the invention is to provide a signal of this character which shall be simple and certain in its action even when manipulated by an excited person, easy to install and to maintain, and which may serve as a trouble 10 lamp or for other purposes when required, having the double advantage of economy and constant testing to ensure operative condition.

I attain my object by providing a base 15 plate or support adapted to be secured upon the back of the operator's hand in such fashion that the fingers may be left free for ordinary use, as for example for grasping and manipulating the steering wheel; and upon 20 this support I mount a lamp casing fitted with a bull's eye in its top or outer side but open on its bottom next to the base plate to which it is secured by readily detachable fasteners such as studs working in slots. A 25 flexible cord leads from the lamp in the casing to suitable terminals on the vehicle, through which current is derived from the ordinary lighting circuit thereof. In use, this device enables a driver to signal at all 30 times both day and night, in a uniform manner, using the hand only, without the necessity of setting levers or other pieces of apparatus. In emergencies the simplicity of 35 this method of signaling is a very important factor, as it reduces the liability to error to a minimum.

The constant use of this device in signaling insures the good condition of the lamp, which cannot burn out or become 40 otherwise inoperative without the operator's knowledge. This is an important feature, as by detaching the lamp casing from the support, said casing having its bottom open, the lamp immediately becomes available as 45 a trouble lamp or for general illuminating purposes. Trouble lamps are ordinarily stowed away in the kit until needed, and are liable to be found mechanically or electrically defective in an emergency.

50 My invention is illustrated in the accompanying drawings in which, Fig. 1 is a plan view of the base plate with combined signal and trouble lamp mounted thereon. Fig. 2 is a section thereof on the line $\alpha-\alpha$ of Fig. 1

with the lamp and its connections in full 55 lines. Fig. 3 is a rear view of the lamp casing and lamp detached. Fig. 4 is a perspective view showing the manner of mounting the device as a whole on the back of the operator's hand. 60

Referring to the drawings, 1 is a plate made of light and stiff material such as aluminum, having secured upon it, as by rivets 4, a pair of cross straps 2 and 3, each fitted with a series of snap fasteners 2^a or 65 3^a, which may be replaced by buckles or any other convenient means for adjustably fastening the straps. The strap 2 passes around the palm of the operator's hand, and the strap 3 passes around the wrist as shown 70 in Fig. 4. It will be observed that by this mode of fastening the hand is left entirely free for ordinary use, such as grasping the steering wheel.

Upon the upper part of the plate 1, so 75 that it will come directly above the fingers of the hand, I mount a lamp casing 6 having a bull's eye 7 of red glass, and containing a lamp 18 mounted in a socket 12 extending through the side wall of the casing and 80 adapted to receive in its outer end the terminal plug 14 of a lamp cord 15 connected in any desired manner to the storage battery or other source of current carried by the vehicle. As indicated in Fig. 4, this cord 85 hangs loosely from the operator's arm without impeding the free use of the hand.

The casing 6 has a flange 5, in which are 90 formed two arc shaped slots 8 and 9 to receive studs 10 and 11 oppositely secured on a metal ring 1^a riveted to the base plate 1. One end of each slot 8 or 9 is enlarged to 95 pass the head of the corresponding stud 10 or 11 so that the casing may be detached by simply rotating it through the arc of the slots until the studs reach the enlarged ends thereof.

Referring to Figs. 2 and 3, it will be observed that the bottom of the casing 6 is 100 open when detached from the base plate, Fig. 3 being in effect a front view of the device used as a trouble lamp. The interior of the bull's eye serves in this case as a partial reflector, and a supplemental reflector, of white or polished material, may be provided to slip in behind the lamp in the casing 105 for greater efficiency in illumination.

As a corollary to the above, the lamp may

be removed and the plate 1 used alone for signalling in the day time. I paint it red when to be so used.

Having thus described my invention, I
5 wish it to be understood that various
changes can be made in matters of detail
without departing from the scope and pur-
view thereof, and that I contemplate all
10 such changes and modifications as fall fairly
within the scope of the appended claim.

I claim:

15 In a device of the class described, the
combination of a flat signal plate of stiff
light material of such proportions as to
cover the back of the hand from the wrist to
the finger tips, of proper shape and color to
20 constitute a proper daylight danger signal, a
plurality of straps attached thereto at points
intermediate the ends, arranged to embrace

the hand just back of the knuckles and at 20
the wrist, leaving the fingers and thumb free
for use, a separate lamp casing open on one
side and closed on the other by a lens of
colored glass to constitute a night danger
25 signal, an integral flange formed around the
edge of the open side of same, and shaped
to fit closely and directly against the face
of the signal plate, cooperating quick de-
tachable fastening means on said casing and
30 on said plate respectively, whereby the lamp
unit as a whole, including the lamp and its
casing, may be mounted on the plate for use
at night, and may be detached therefrom in
the daytime, or for special use at any time
35 as a trouble lamp.

In testimony whereof I hereunto affix my
signature.

HENRY R. SANDERS.
